UNITED STATES PATENT OFFICE.

IGNATZ H. FREUND, OF CHICAGO, ILLINOIS, ASSIGNOR TO FEDERAL CEMENT TILE COMPANY, OF CHICAGO, ILLINOIS, A CORPORATION OF ILLINOIS.

CEMENT-MORTAR OR CONCRETE ROOFING-TILE.

1,089,373.

Specification of Letters Patent.

Patented Mar. 3, 1914.

Application filed March 15, 1912. Serial No. 684,061.

To all whom it may concern:

Be it known that I, IGNATZ H. FREUND, a citizen of the United States, residing at Chicago, in the county of Cook and State 5 of Illinois, have invented a new and useful Improvement in Cement-Mortar or Concrete Roofing-Tile, of which the following is a specification.

The use of cement-mortar or concrete 10 roofing-tile as hitherto provided is objectionable, under some conditions, in that they are of such construction as to cause condensation of moisture on their under surfaces when forming a roof of a room in 15 which the air is humid; and furthermore, by reason of their solidity, do not properly insulate the atmosphere from the air in the room.

My object is to provide a cement-mortar 20 or concrete roofing-tile of such construction as will obviate, as nearly as possible, condensation of moisture thereon from the air in the room of which they form the roof, and shall possess insulating properties, 25 against heat and cold, to a high degree; and to this end I form the tile with one or more closed chambers therein, thereby forming dead-air spaces disposed between the upper and lower portions of the tile, which serve 30 to overcome the objections above noted.

Referring to the accompanying drawings in which my invention is shown as embodied in one of a number of forms of tile in which it may be utilized, Figure 1 is a plan view 35 of a section of a roof constructed of tile embodying my invention, certain of the tile units being shown in plan section, the section on which the lowermost one of the sectioned tile is taken being represented at a 40 in Fig. 6, and the section on which the other sectioned tile is taken being represented at y. Fig. 2 is a section taken at the line 2 on Fig. 1 and viewed in the direction of the arrow. Fig. 3 is an end view of one of the 45 similar tiles. Fig. 4 is a broken section taken at the line 4 on Fig. 3 and viewed in the direction of the arrow; and Figs. 5 and 6, sections taken at the lines 5 and 6 respectively on Fig. 1 and viewed in the directions of the arrows.

The tile illustrated in the drawings, in so far as their external formation and manner of assembling to form a roof is concerned, are substantially the same as those com-

monly provided, each tile being relatively 55 long, wide and thin and presenting along its marginal edges on its upper surface longitudinally extending flanges 7, which, when the tile are positioned in staggered, overlapping relation as represented in the drawings, on the purlins, represented at 8 and spaced apart as is usual in constructions of this character and forming a part of the skeleton roofed-structure 9, are inclosed by channelled bars 10 of concrete to cover the 60 abutting joints between adjacent tile, the lower ends of the tile on their under surfaces containing concaved recessed portions 11 which extend longitudinally of the tile and which, when the tile are positioned as 65 illustrated, are superposed on and cover, the adjacent ends of the channelled bars 10, as represented in Figs. 1 and 2, thus permitting the tile to lie flatwise at their overlapping ends against the adjacent tile. 75

The tile illustrated, instead of being solid as hitherto provided, contain closed chambers represented at 12, each tile preferably containing a single chamber, though if desired a plurality of closed chambers of any 80 suitable number may be provided therein, the chambers in the tile illustrated extending closely adjacent to the marginal edges of the tile, whereby chambers of relatively great area, as compared with the area of the 85 tile, are provided therein.

The chambers 12 in the tile may be formed from cement-mortar or concrete in any desirable manner, but preferably in the operation of molding the tile in accordance 90 with the methods well-known to those skilled in the molding art, whether it be by having the cores, for forming the chambers, extend part way into the molds for molding the tile with chambers each closed, in the 95 molding operation, at one end only and thereafter plugging at its opposite end with the same material as that from which the tile is molded, or any other suitable material, to render the chambers closed; or by 100 having the cores extend entirely across the mold and thereafter plugging up the ends of the openings produced thereby in the tile, to render the chambers closed; or by molding into the tile a tube or tubes, of any 105 suitable material, which reach short of the mold and form a part of the tile when completed; or by forming them in any other

suitable manner to produce the desired closed chambers.

Where the tile are formed with chambers of relatively great area as compared with the area of the tile, it is desirable that reinforcing means therefor be provided. Desirable means for this purpose are illustrated in the drawings, wherein 13 represents a reinforcing wire-mesh embedded in the bottom sections of the tile.

It will be observed that each tile containing a closed chamber, or chambers, as the case may be, constitutes a separate unit presenting a dead-air space or spaces which are independent of the air-spaces in adjacent tile and are out of communication therewith and thus do not depend for their closure, to prevent circulation of air therethrough, upon the cementing of any joints between the open ends of adjacent tile, thereby avoiding danger of circulation of air through the air chambers in the tile.

While I have shown my invention as embodied in a roofing-tile of a particular type, I do not wish to be understood as intending to limit it to such embodiment or to its embodiment in tile which when assembled to form a roof occupy the staggered overlapping position illustrated, as it may be embodied in any other type of cement-mortar or concrete roofing-tile and in tile designed to be assembled in end abutting relation or other desirable relation and wherein it is desirable that a closed chamber or chambers, forming a dead-air space or spaces, be provided in each tile unit.

It will be manifest that by constructing tile in accordance with my invention a roof may be formed of tile units which are relatively long and wide and thin, and still present insulating bodies of dead-air of area sufficient to prevent, or at least greatly minimize, condensation of moisture on the under side of the roof, and in addition thereto effectually insulate the air on one side of the roof from the air on the opposite side of the roof.

What I claim as new and desire to secure by Letters Patent is:

1. A roofing tile comprising a flat body portion formed on its upper longitudinal edges with longitudinal flanges, and at its upper forward edge with a transverse depending flange, the rearward under surface of the tile having a longitudinal recess open at its end and bottom, and the tile about and beyond said recess being hollow to form a dead-air space.

2. A plurality of hollow roofing tiles adapted to be laid in overlapping and interlocking series, each tile being formed with longitudinally extending marginal flanges on its upper surface and containing a closed chamber affording a dead-air space, and a recess on the under side of the tile the side and end walls of which intersect said closed chamber and lying in the same longitudinal plane therewith, and channel members adapted to cover abutting flanged edges of flanking tiles, the end of each channel member fitting in one of said recesses, whereby each tile of the series is caused to lie in flatwise relation over the end of an adjacent tile.

3. A plurality of hollow reinforced roofing tiles adapted to be laid in overlapping and interlocking series, each tile being formed with longitudinally extending marginal flanges on its upper surface and containing a closed chamber affording a dead-air space, and a recess on the under side of the tile the side and end walls of which intersect said closed chamber and lying in the same longitudinal plane therewith, and channel members adapted to cover abutting flanged edges of flanking tiles, the end of each channel member fitting in one of said recesses, whereby each tile of the series is caused to lie in flatwise relation over the end of an adjacent tile.

IGNATZ H. FREUND.

In the presence of—

JOHN WILSON,
RALPH SCHAEFER.
